(57) **CLAIM**

The ornamental design for a mobile phone, as shown and described.

DESCRIPTION

FIG. 1 is a perspective view of a mobile phone;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is an enlarged top plan view thereof;
FIG. 8 is an enlarged bottom plan view thereof;
FIG. 9 is an enlarged view of area 9 circumscribed in FIG. 1;
FIG. 10 is an enlarged view of area 10 circumscribed in FIG. 2;
FIG. 11 is an enlarged view of area 11 circumscribed in FIG. 2;
FIG. 12 is an enlarged view of area 12 circumscribed in FIG. 4;
FIG. 13 is an enlarged view of area 13 circumscribed in FIG. 5;
FIG. 14 is an enlarged view of area 14 circumscribed in FIG. 5;
FIG. 15 is an enlarged view of area 15 circumscribed in FIG. 6;
FIG. 16 is an enlarged view of area 16 circumscribed in FIG. 6; and,
FIG. 17 is an enlarged view of area 17 circumscribed in FIG. 6.

The broken lines consisting of evenly spaced short dash lines in the drawings depict portions of the mobile phone that form no part of the claimed design.

(Continued)

The broken lines consisting of long and short dash lines in the drawings depict the boundaries of the enlarged views and form no part of the claimed design.

The oblique shade lines in the drawings show transparency.
